Heriam W. Hayden of Waterbury Conn.
Letters Patent No. 733, dated Oct. 9, 1855.

The Schedule referred to in these Letters Patent & making part of the same

To all to whom these Presents shall come:

Be it known that I Heriam W. Hayden of Waterbury in the county of New Haven & State of Connecticut have invented or produced a new and original design for ornamenting flattings used for Slaguerrelye pictures or similar purposes, and I do hereby declare that the following is a correct description of the same, reference being had to the annexed drawing making part of this Specification, wherein figure 1. represents the Matting & figure 2. is a section of the same.

The ornaments are struck onto the surface of the metal by suitable dies actuated by competent pressure. The size and shape of die for impressing the ornamental design being adapted to the desired matting.

The design for the ornament surrounding the opening in the matting, represents flowers and leaves, raised so as to have the appearance of a wreath, as shewn in the drawing.

The design to be stamped on the flat surface of the plate, - between the ornaments around the opening and the edge of the matting, - is formed of rows of diamond shaped raised ornaments, with a small figure resembling

Des. 733

four leaves, depressed in the centre of each, as shown in the drawing.

I claim the design of the ornament surrounding the opening in the malting, and also the design of the ornament formed on the surface of the malting as shown in the drawing.

In witness whereof I have hereunto set my signature
this Sixth day of September 1855. —

Witnessed
